UNITED STATES PATENT OFFICE.

WILLARD F. LEWIS, OF SWAMPSCOTT, MASSACHUSETTS, ASSIGNOR OF
ONE-THIRD TO FRANK F. STANLEY, OF SAME PLACE.

TROLLEY.

SPECIFICATION forming part of Letters Patent No. 427,333, dated May 6, 1890.

Application filed March 7, 1890. Serial No. 342,970. (No model.)

To all whom it may concern:

Be it known that I, WILLARD F. LEWIS, of Swampscott, county of Essex, State of Massachusetts, have invented an Improvement in 5 Trolleys, of which the following description, in connection with the accompanying drawings, is a specification, like letters and figures on the drawings representing like parts.

This invention relates to electric-railway systems of that class known as the "overhead" system, in which the electric power is taken from a trolley-wire and conveyed to the motor on the car by means of a trolley-pole.

In the overhead system of electric railways as now commonly constructed considerable difficulty is experienced when the overhead trolley-wire is carried across a railroad-track, inasmuch as the trolley-wire is broken or disconnected to permit the railroad-gate extended across the street or roadway when closed to be elevated into its upright position when the gate is opened. The current to the electric motor on the car is broken when the trolley-wheel passes by the broken space in the 25 trolley-wire, thereby giving rise to accidents.

This invention has for its object to provide apparatus by means of which the current or electricity may be continuously supplied to the motor when the car is passing over a railroad-track, and I accomplish my object, as herein shown, by providing the trolley-pole with an independent arm carrying a trolley-wheel, the said independent arm being made shorter than that portion of the pole beyond 30 the junction of the said arm with the said pole.

The particular features in which my invention consists will be pointed out in the claim at the end of this specification.

Figure 1 represents a sufficient portion of 40 an electric-railway system embodying my invention to enable it to be understood, the electric car being shown in two positions, one just previous to crossing the railroad-track and the other partially over the said track. 45 Fig. 2 is a top or plan view of the portion of the trolley-wire located above the railway-track, and Fig. 3 a detail to be referred to.

The trolley-wire *a*, located above the road-bed and supported in usual manner from span-wires secured to posts *a'*, located at the sides 50 of the road-bed, may be of any usual construc-

tion. That portion of the trolley-wire *a* located above the railway-track and marked 2 in Fig. 1 is herein shown as carried up higher than the main portion of the trolley-wire 55 (marked 3.) The portion 2 of the trolley-wire above the railway-track and substantially in the path of movement of the railway-gate *a*² (see Fig. 3) is carried out to the side of the road to form a loop *b*, as clearly shown in Fig. 2, there being one such loop for each gate *a*². The loop *b* may, and preferably will, be an independent wire or conductor electrically connected to the sections of the trolley-wire on opposite sides of the break therein; but it may 65 form an integral part of the said wire. It will thus be seen that the circuit of the trolley-wire across the railroad-track is unbroken.

In order that the current may be taken continuously from the trolley-wire and supplied 70 to the motor on the car *b'* when the car is passing over the railroad-track, I have provided the usual trolley-pole *b*², having at its end the trolley-wheel *b*³, with an arm *b*⁴, having a trolley-wheel *b*⁵. The arm *b*⁴ is secured 75 to the trolley-pole *b*², and the trolley-wheels *b*³ *b*⁵ are both electrically connected in any usual manner with the motor on the car.

The trolley-arm *b*⁴ is made shorter than that portion of the trolley-pole *b*² beyond the point 80 at which the said arm is secured to the said pole, so that when the car *b'* is running on the main portion of the road the trolley-wheel *b*⁵ is in contact with the trolley-wire *a*, and the current is supplied to the motor on the 85 car through the arm *b*⁴ and pole *b*².

When the electric car is passing over the railroad-crossing, the trolley-pole *b*², which is pivotally supported in any usual manner to the top of the car, is turned from the oblique 90 position shown at the right in Fig. 1, to a more nearly vertical position, as shown at the left in Fig. 1, so that when the trolley-wheels are passing by the break in the trolley-wire one wheel, as *b*⁵, will be in contact with the 95 portion of the trolley-wire on one side of the break, and the trolley-wheel *b*³ will be in contact with the portion of the trolley-wire on the other side of the break, so that the current from the trolley-wire is supplied continuously to the motor on the car. 100

As herein shown, the trolley-wheel *b*⁵ will

be in contact with the trolley-wire until the break is reached; but as soon as the break in the trolley-wire is reached in the travel of the car the trolley-wheel b^3 will be brought 5 into contact with the trolley-wire just before the trolley-wheel b^5 leaves or breaks contact with the said wire, and when the trolley-wheel b^3 passes by the break in the trolley-wire the wheel b^5 will at such time be in contact with the said trolley-wire. It will thus 10 be seen that the circuit of the motor will always be complete between the trolley-wheel and the trolley-wire as the car is passing across a railroad-track, and the gates a^2 are 15 free to be operated in the usual manner.

I claim—

The combination, with an electric-railway car, of a trolley-pole pivoted thereto and provided with a trolley-wheel or contact-maker, and an independent arm connected to the 20 trolley-pole and provided with a trolley-wheel or contact-maker, to operate substantially as described.

In testimony whereof I have signed my name to this specification in the presence of 25 two subscribing witnesses.

WILLARD F. LEWIS.
